UNITED STATES PATENT OFFICE.

HOWARD R. HUGHES, OF HOUSTON, TEXAS, ASSIGNOR TO HUGHES TOOL COMPANY, OF HOUSTON, TEXAS, A CORPORATION OF TEXAS.

ROTARY BORING-DRILL.

1,256,694.

Specification of Letters Patent. Patented Feb. 19, 1918.

Application filed December 26, 1916. Serial No. 138,319.

To all whom it may concern:

Be it known that I, HOWARD R. HUGHES, a citizen of the United States, residing at Houston, Texas, have invented a certain new and useful Improvement in Rotary Boring-Drills, of which the following is a full, clear, and exact description, such as will enable others skilled in the art to which it appertains to make and use the same.

10 This invention relates to boring drills, and particularly to roller drills such as are used for boring holes in earth, rock, concrete and other hard substances. One object of my invention is to provide a drill of 15 the type referred to which is compact and strong and composed of a few large parts.

Another object is to provide a roller drill in which the roller cutters are mounted in a pocket, the side walls of which extend over 20 a substantial portion of the cutters, forming a shroud protecting them.

Another object is to provide a roller drill in which the water holes for admitting flushing water to the bottom of the hole being 25 drilled, are so arranged that their outlets are very close to the material upon which the drill is operating, and which are so arranged that the water issuing from these holes impinges directly upon the surface 30 being drilled. Other objects and desirable features of the invention will be hereinafter pointed out, and will clearly appear in the description of my device.

In the drawings which illustrate the preferred form of my invention, and in which like characters of reference designate like parts,

Figure 1 is a side elevation of the assembled device, certain features being shown 40 therein in dotted lines.

Fig. 2 is an end view of the assembled device illustrated in Fig. 1.

Fig. 3 is a side elevation of one of the members of the drill head.

45 Referring to the drawings, 1 designates two members that coöperate with each other to form the head of the drill, the meeting faces 2 of which members are plane surfaces arranged parallel to the longitudinal axis 50 of the drill head. Each of the members 1 is provided with a reduced portion 3, such reduced portions being externally threaded, and adapted when the two members of the drill head are placed together, to coöper-

ate to form a threaded neck adapted to receive a drill collar, 12, which collar can be of any ordinary construction. This collar when screwed in place upon the neck 3, holds the members of the drill head in assembled position. Upon each reduced portion 3, is a still further reduced portion 4, which is also threaded and adapted when the drill head is assembled to receive a lubricant container for furnishing lubricant to the various surfaces in the drill requiring such. Formed in the end of each member 1, is a recess 5, one wall 13 of which, as shown in dotted lines in Fig. 1, is inclined to the longitudinal axis of the drill head. For convenience this wall 13 will be called 70 the bottom wall of the recess. The side walls 6 of these recesses are extended inwardly along the meeting faces of the members 1 so as to give to these side walls a shape which is substantially triangular in 75 cross section, as clearly shown at 6 in Fig. 2. The walls 6 decrease in size from the bottom of the recess 5.

Mounted in the recess in each member 1 is an approximately conical shaped cutting 80 roller 7. These rollers are mounted upon spindles 8, which are in turn rigidly attached to the members 1. The precise form of these rollers and the method of mounting forms no part of this invention, these 85 features having heretofore been fully covered in several of my earlier patents, and any form of roller and mounting therefor, disclosed in my prior patents showing such features, may be used in the device forming 90 the subject matter of this invention.

Such rollers, however, should be so proportioned and so arranged that the un-housed part of the rollers will extend beyond the outer surface of the drill head to 95 thus cut a hole of greater diameter than the drill head, so as to prevent any sticking or binding of the drill in the hole which it cuts.

Extending through the drill head from 100 the threaded extension 4, are lubricant ducts 15, leading to the bearings 8.

Formed in the meeting faces of the members 1, are longitudinal grooves 10. These grooves extend throughout the length of the 105 drill head, and are so arranged that they will register when the drill head is in assembled position to form continuous pas-

- sages through the drill head. The upper ends of these grooves or passages are so arranged that water forced down through the drill stem will have ready access thereto and will flow through the passages. As clearly shown in Fig. 1, the side walls 6 are extended so as to cover a substantial portion of the cutting rollers, and are therefore in proximity to the bottom of the hole when the drill is in use. The water passages 10 are extended down through the walls 6, and are so arranged that any water forced therethrough will issue from the bottom ends of the passages at points substantially at the bottom of the walls 6 in jets which are unobstructed by any of the drill structure, and which will impinge directly upon the surface being operated upon by the drill.
- 20 As shown at 11 the members of the drill are flattened or cut away upon each side so as to afford a larger passage-way between the outer surfaces of the drill head and the wall of the hole being bored, thus enabling the flushing water introduced to the bottom of the hole through the water passages to more readily carry off the cuttings and disintegrated material from the bottom of the hole.
- 30 In assembling the device the cutting rollers 7 are placed in position and the two members 1 placed with their meeting surfaces in contact, so that the threads on the extensions 3 will register to form a continuous thread. A drill collar is then screwed upon this extension 3, thus holding the members of the drill head together, with the cutting rollers in operative position. When so assembled, the grooves 10 register to form continuous water passages as set forth above, and the recesses 5 also register, forming a pocket having the side walls 6. These side walls because of their triangular shape, extend inwardly between the cutting rollers and form a shroud or housing for a substantial portion of both cutters. From this structure it is evident that the shrouds 6 extend to within a short distance of the bottom of the hole and that jets of water issuing from the water passages will be unobstructed and will strike directly against the bottom of the hole.
- Having thus described my invention, what I claim as new and desire to secure by Letters Patent is:
- 55 1. A drill provided with a head, a pocket in the end of the head having the end walls thereof inclined, cutting rollers mounted in the pocket on the inclined end walls thereof, the side walls of the pocket being so extended as to house the major portion of the rollers.
- 60 2. A drill provided with a head, a pocket in the end of the head having the end walls thereof inclined to the longitudinal axis of

the head, approximately conical shaped cutting rollers mounted in the pocket on the inclined walls thereof, the side walls of the pockets forming a housing for the cutting rollers, a substantial portion of the rollers being thus housed.

3. A drill comprising a head composed of a plurality of parts, a recess in the end of each part, the end wall of each recess being inclined to the longitudinal axis of the drill head, a cutting roller mounted on the inclined end wall of each recess, the recesses being adapted to register when the drill head is assembled, so as to form a pocket in which the cutting rollers are partially housed, the side walls of such pocket forming a protecting shroud for the rollers.

4. A drill provided with a head, a pocket in the end of the head, cutting rollers mounted in the pocket, the side walls of the pocket forming a housing covering a substantial portion of the cutting rollers, water passages extending through the drill head and through the side walls of the pocket, said passages being so arranged that jets of water issuing therefrom will strike upon the bottom of the hole being cut by the drill.

5. A drill provided with a head composed of a plurality of members, recesses in the ends of these members, cutting rollers mounted in the recesses, the side walls of the recesses forming a housing for a substantial portion of the cutting rollers.

6. A drill provided with a head, a pocket in the end of the head, cutting rollers mounted in the pocket, the side walls of the pocket forming a housing for a substantial portion of the cutting rollers, water courses in the head, portions of the head being cut away to permit the ready passage of water there-around when the drill is in operation.

7. A drill provided with a head, a pocket in the end of the head, cutting rollers mounted in the pocket, the side walls of the pocket forming a housing for a substantial portion of the cutters, the side walls extending partly between the cutters, water courses in the drill head extending through the side walls, so that the water passing therethrough will impinge directly upon the bottom of the hole being cut by the drill.

8. A drill comprising a head composed of a plurality of parts, the meeting faces of which lie in a plane parallel to the longitudinal axes of the head, recesses in the ends of the parts, the end walls of which are inclined relative to the plane of meeting of the parts of the head, substantially cone shaped cutters mounted in the recesses, longitudinal grooves in the meeting faces of the parts of the head, the recesses being adapted to register to form a pocket the side walls of which pocket house a substantial portion of the cutters and the grooves to register to form a water passage when the

drill is in assembled position, the lower portions of the grooves passing through the side walls of the pocket and terminating near the bottom end thereof, the outer surfaces of the parts of the drill head being cut away, the cut-away portions being adapted to register when the drill is in assembled po-

sition to form channels for the passage of fluid therethrough.

In testimony whereof, I hereunto affix my signature this the 22nd day of December, 1916.

HOWARD R. HUGHES.
